US00D576682S

(12) United States Design Patent
Beyer

(10) Patent No.: US D576,682 S
(45) Date of Patent: * Sep. 9, 2008

(54) WRITING UTENSIL HOLDER

(75) Inventor: Hans-Juergen Beyer, Ober-Ramstadt (DE)

(73) Assignee: Senator GmbH & Co KGaA (DE)

() Term: 14 Years

(21) Appl. No.: 29/254,677

(22) Filed: Feb. 28, 2006

(30) Foreign Application Priority Data

Aug. 30, 2005 (DE) 405 04 548

(51) LOC (8) Cl. 19-06

(52) U.S. Cl. D19/85

(58) Field of Classification Search D3/201, D3/206; D6/467, 476; D19/54, 75-85; 206/1.7, 214; 211/69.1-69.9, 70.1
